UNITED STATES PATENT OFFICE

94,891

DESIGN FOR A MIRROR PLACE CARD

Olive Read Graf, Los Angeles, Calif.

Application December 8, 1934, Serial No. 54,351

Term of patent 3½ years

To all whom it may concern:

Be it known that I, Olive Read Graf, a citizen of the United States, residing at Los Angeles, in the county of Los Angeles and State of California, have invented a new, original, and ornamental Design for Mirror Place Cards, of which the following is a specification, reference being had to the accompanying drawing, which forms a part of said specification.

The figure of the drawing is a face view of a mirror place card, showing my new design. The dominant feature of my design is a rectangular panel on the front surface of the mirror place card, as indicated by the stippled portion of the drawing, the surface of said panel having a frosted appearance.

I claim:

The ornamental design for a mirror place card, as shown and described.

OLIVE READ GRAF.
